(57) **CLAIM**

The ornamental design for a payment card with a 3CVV display, as shown and described.

DESCRIPTION

FIG. 1 is a front elevational view of a payment card with a 3CVV display showing my new design; and,

FIG. 2 is rear elevational view thereof.

The broken line showing of personal card numbers is included for the purpose of illustrating environmental structure and forms no part of the claimed design.

The broken line showing of personal card numbers illustrates environmental structure and forms no part of the claimed design.
